COMBINED DESK CALENDAR AND TELEPHONE INDEX

Wallace A. Monson, Minneapolis, Minn., assignor to
Brown & Bigelow, St. Paul, Minn., a corporation of
Minnesota

Filed Dec. 23, 1959, Ser. No. 58,772

Term of patent 14 years

(Cl. D74—5)

FIG. 1

FIG. 2

FIG. 3

FIG. 4

FIG. 5

FIG. 6

Fig. 1 is a front perspective view of a combined desk calendar and telephone index, showing my new design;

Fig. 2 is a front perspective view thereof as it appears with the telephone index in open position;

Fig. 3 is a top plan view of the design as shown in Figure 1;

Fig. 4 is a side elevational view thereof;

Fig. 5 is a front elevational view thereof; and

Fig. 6 is a rear elevational view thereof.

The essential features of the design reside in the portions shown in solid lines on the drawing.

I claim:

The ornamental design for a combined desk calendar and telephone index, as shown and described.
